Specification of Letters Patent. Patented Mar. 28, 1911.

Application filed April 23, 1909. Serial No. 491,681.

To all whom it may concern:

Be it known that we, JAMES E. CLENNY and WALTER H. FAIRCHILD, citizens of the United States, residing at Chicago, Illinois, 5 have invented certain new and useful Improvements in Packing or Shipping Boxes, of which the following is a specification.

Our invention relates to what are generally referred to as packing and shipping 10 boxes made of paper or paper board, and intended for the packaging and shipping of articles, and the object thereof is to provide for a box of this general character a buffer or cushion or series thereof so constructed 15 and arranged in the box as to permit of the safe packing and shipping more particularly of fragile articles, such as glassware, crockery, tungsten lamps, etc.

Speaking in general terms, our invention 20 consists in providing particularly but not necessarily for use between the shell or body of the box and the article or articles contained therewithin resilient buffers or cushions preferably made of the same material 25 as the box itself, which in practice is what is known as double faced corrugated paper board. By properly forming and bending strips of this corrugated board we are enabled to provide efficient yielding buffers 30 having sufficient spring or resiliency to fully protect the contents of the box against injury from blows or shocks.

Other features of utility and advantage 35 in our buffer or cushion and also new construction of box embodying the same will be apparent from the description hereinafter given.

In the drawings, Figure 1 is a plan view 40 of a blank from which the body of the box is formed; Fig. 2 a perspective of the box proper formed from the blank of Fig. 1; Fig. 3 a plan view of a blank from which one of the larger resilient buffers is formed; Fig. 4 a similar view of a blank for one of 45 the smaller size buffers; Fig. 5 a perspective of an interior open ended shell preferably but not necessarily used for containing articles to be packaged or shipped; Fig. 6 a

perspective of a complete box embodying 50 our invention and partially cut away to expose the interior construction thereof; Fig. 7 a horizontal section of said box; Fig. 8 a vertical section thereof; Fig. 9 a perspective of one of the buffers; and Fig. 10 a view of a modification thereof. 55

Referring to the present embodiment of our invention as illustrated in the drawings, the box proper is formed from any suitable material so far as our invention in its broader aspect is concerned but in the present instance and by preference it is formed from a single piece of paper board, preferably double faced corrugated paper board, which is scored and cut in the manner indicated in Fig. 1, thereby forming the four 60 similar side walls 1 and the similar end flaps or extensions 2. In forming the box as shown in Fig. 2 the outermost end walls are brought together and their edges suitably hinged together as by means of the strip or 65 tape 3. It will be understood that the end flaps 2 of one end of the box which is to form the bottom thereof are folded inwardly and suitably secured and the interior structure of the box is then introduced and the 70 articles also introduced, after which the top extensions are folded in proper manner and secured in such a way as to close and seal the 75 box. This particular construction of box proper, however, it will be understood, is 80 immaterial so far as our present invention is concerned and the same is herein shown as an efficient box construction for the purposes in view.

By preference we employ an open-ended 85 shell of smaller dimensions than the box proper and consisting of the four side walls 4 hinged together and preferably made of double faced corrugated paper board. Although, if desired, a complete box with top 90 and bottom, such as one similar to the outer box, might be employed, or if desired loose paper boards may be used to close the top or bottom or both of the shell. It is within this shell that the article or articles to be 95 packaged and shipped are placed. This shell

is sufficiently smaller in size than the box proper to leave intervening spaces on all sides as well as at top and bottom thereof. In these spaces are introduced what we term 5 buffers which may be of any number but which in the present instance are of a number to completely fill all of said spaces. As herein shown, these buffers are of two different sizes, the larger size being placed in 10 the spaces at the open ends of said shell, but the construction and arrangement of the buffers is precisely the same except as to size.

The larger sized buffers are each formed 15 from the blank 5 illustrated in Fig. 3, which blank is scored in the manner there indicated and is bent so as to assume the form illustrated in Fig. 9, where it is seen that the buffer consists of two parallel portions and 20 interposed resilient portions 5^a. However, if desired to increase the amount of resilient action, the number of these interposed resilient portions may be increased as made apparent by Fig. 10 where a series of four 25 of such portions 7^a is used along each side of the buffer 7. The smaller sized buffers are formed from a blank 6 which is similar to the blank 5 but narrower, as indicated in 30 Fig. 5. This blank 6 is scored or creased in the same manner as the other blank so as to 35 form a similar buffer. By preference these buffers are made of the same material as the body of the box, that is double faced corrugated paper board, which is found in practice to give sufficient strength and resiliency 40 for the desired purposes. It will, however, be understood that any other material may be used which when folded in the manner described will exhibit similar qualities.

45 In practice one end of the box proper which is to constitute the bottom thereof is closed and sealed and two of the larger buffers 5 are introduced into the box and placed upon the bottom thereof, as seen in Fig. 8, these buffers being here shown as of a sufficient size to completely fill the bottom of the box; that is to say, two of the buffers 5 have the same area as the bottom of the box. Assuming that a shell 4 is employed, the same is 50 now introduced and rested upon the buffers 5 just referred to, whereupon the article or articles to be packaged or shipped are introduced in the shell. Either before or after the introduction of the article into the shell 55 a series of the smaller sized buffers 6 are introduced in the spaces between the sides of the shell and the box proper, these buffers resting upon the buffers 5 at the bottom of the box. These side buffers, if intended 60 to occupy the entire space between the sides of the shell and the box proper, are of two different widths, as clearly indicated in Fig.

7, the wider buffers extending into the corners of the box proper. Thereupon two more buffers 5 are introduced into the box, 65 the same being placed flat upon the shell 4 and the other buffers 6 which are in vertical position as clearly indicated in Figs. 6 and 8. The extensions or flaps 2 which constitute the top of the box are now properly folded 70 and closed. By preference the top and bottom of the box are securely sealed, and the buffers are caused to fit rather closely with respect to each other and with respect also to the other parts of the box structure, with 75 the result that these buffers have pneumatic functions inasmuch as a blow or jar against the side of the box is transmitted to the adjacent buffer and as the air therein is practically confined, the force of the blow will 80 be cushioned by the contained air as well as by the resilient action of the buffers. The article or articles within the box are thus protected against shock or jar so that the most fragile articles, particularly tungsten lamps, 85 may be safely packaged and shipped. In the case of the more fragile articles, we prefer to interpose between the articles and the box proper a complete envelop to protect the articles in the manner indicated in the 90 drawings, but as will be understood a less number of such buffers might be employed for less fragile articles, any suitable means being preferably employed for holding the buffers in place. It will also be understood 95 that it is not necessary to employ the shell 4, in which event the buffers would be interposed directly between the article and the body of the box.

We claim.

1. A buffer for packing or shipping purposes comprising a strip of elastic paper board or the like transversely folded to form two opposite flat bearing sides and, hinged at opposite edges of said sides, two 105 pairs of inwardly bent leaves hinged together at their edges to form reentrant resilient portions.

2. A buffer for packing or shipping purposes comprising a relatively wide strip of 110 paper board or the like transversely folded to form two opposite flat bearing sides and, hinged at corresponding edges of said sides, a series of relatively long leaves inwardly bent from such edges and hinged together in 115 accordion folds to form a resilient portion.

3. A packing or shipping box comprising a box body and a series of buffers arranged on the inner walls of the box body and between it and the goods contained therein, 120 each buffer consisting of a strip of paper board folded into tubular form and arranged with the ends thereof abutting flat walls so as to act as an air cushion.

4. A packing or shipping box comprising a box body adapted to be sealed so as to be air-tight, and a series of buffers arranged on the inner walls of the box body and between it and the goods contained therewithin, each buffer consisting of a strip of paper board transversely folded to form a flattened tube with opposite sides inwardly folded

for resilient action, said buffers being formed and fitted within the box body so as to be practically air-tight.
